UNITED STATES PATENT OFFICE.

THOMAS W. G. COOK, OF NEW YORK, N. Y.

BUTTON.

SPECIFICATION forming part of Letters Patent No. 350,042, dated September 28, 1886.

Application filed March 18, 1886. Serial No. 195,721. (No model.)

To all whom it may concern:

Be it known that I, THOMAS W. G. COOK, a citizen of the United States, residing at New York, in the county and State of New York, 5 have invented new and useful Improvements in Buttons, of which the following is a specification.

My improvement relates to an improved fastening for gloves, stays, boots, and other articles, the object being to provide a secure fastening, which may be readily attached to the desired article, and which may be easily fastened and unfastened.

The peculiar and novel construction of my 15 button is pointed out in the following specification and claims, and illustrated in the accompanying drawings, in which—

Figure 1 is a view of my button attached to a glove. Fig. 2 is a plan view of the same on 20 a larger scale. Fig. 3 is a section on the line xx , Fig. 5. Fig. 4 is a section on the line yy , Fig. 5, when the spring is removed. Fig. 5 is a section on the line zz , looking in the direction of the arrow. Fig. 6 is the blank from 25 which my button is formed.

Similar letters indicate corresponding parts.

In the drawings, the letter A designates the shell of my button, from the central solid portion of which extend a series of attaching-fingers, a , and expandable and contractible spring-fingers b . In the example shown in the drawings two attaching fingers, a , provided with extensions c , are shown. These extensions are bent to form offsets or shoulders d , and are then passed through springs in the supporting-plate B, so that the shoulders d rest thereon when the protruding portion is bent over said supporting-plate and clinched, thereby firmly securing the shell A to the supporting-plate B. 35 The supporting-plate B may be provided with spurs for fastening to the article upon which the button is to be secured; or it may be sewed or riveted on the same. If desired, more than two attaching-fingers a may be formed on the shell, and the button be fastened to the article directly without the use of a supporting-plate; but I prefer the first-described method. The shell is, by preference, formed of a truncated spherical shape, that portion adjacent to the 45 fastening-plate being of a smaller diameter than the center, so that the latter will form a

shoulder and prevent the eyelet C from slipping up after it has been passed over the button. The spring-fingers b of the button are free at their lower ends, and have sufficient 55 elasticity to permit their being compressed, as the eyelet, which has a slightly smaller opening than the diameter of the shell, is passed over the same, when they will return to their normal position and prevent the accidental slipping off of the eyelet.

To add to the strength and elasticity of the spring-fingers b , I place in the interior of the shell A one or more springs, D, so arranged as to distend the spring-fingers b when at 65 rest, while at the same time permitting the compression necessary for the passage of the eyelet.

The button, formed as shown and described, comprises a spherical or approximately spherical 70 head having a solid central top and bow-shaped spring-fingers, which are radially expandable and contractible, and bow-shaped fingers having extensions for attaching the button to the article or to a base-plate, and also 75 an interior spring for strengthening and contributing to the elasticity of the spring fingers.

What I claim as new, and desire to secure by Letters Patent, is—

1. A button consisting of the shell A, having a series of fingers, a , for attaching it to an article or base-plate, and intermediate said attaching-fingers provided with a series of expandable and contractible spring-fingers, b , the extremities of which are free or unattached, 85 substantially as described.

2. A button consisting of the shell A, formed integral with a solid central top, curved attaching-fingers a , expandable and contractible spring-fingers b , intermediate the attaching fingers and free or unattached at their extremities, and an interior spring, D, for distending the spring-fingers, substantially as described. 90

3. The combination, with the supporting-plate B, of the button-head consisting of the shell A, having the curved fingers a , secured to the plate, and intermediate said attaching-fingers provided with expandable and contractible spring-fingers b , free or unattached at their extremities, substantially as described. 95

4. A button comprising a spherical head formed integral with a central solid top, bow-

shaped attaching-fingers *a*, for securing the button, a series of bow-shaped expansible and contractible spring-fingers, *b*, having free or unattached extremities, and an interior spring,
5 D, for distending the spring-fingers, substantially as described.

In testimony whereof I have hereunto set my

hand and seal in the presence of two subscribing witnesses.
